L. F. Doellinger, by
G. Kennedy,
Attorney.

UNITED STATES PATENT OFFICE.

LOUIS F. DOELLINGER, OF WATERLOO, IOWA.

WRINGER ATTACHMENT.

1,335,957.

Specification of Letters Patent. Patented Apr. 6, 1920.

Application filed July 31, 1919. Serial No. 314,476.

To all whom it may concern:

Be it known that I, LOUIS F. DOELLINGER, a citizen of the United States of America, and a resident of Waterloo, Blackhawk county, Iowa, have invented certain new and useful Improvements in Wringer Attachments, of which the following is a specification.

My invention relates to improvements in wringer attachments, and the object of my improvement is to provide means for preventing clothes from becoming enwrapped about the rolls of a wringer.

This object I have accomplished by the means which are hereinafter described and claimed, and which are illustrated in the accompanying drawings, in which Figure 1 is a perspective view of a clothes-wringer equipped with my improved coacting devices for preventing the enwrapping of clothes about either roll; Figs. 2 and 3 are enlarged perspective detail views of the two coacting devices mentioned; Fig. 4 is a side elevation of a pair of wringer rolls as separated from their frame, and having said devices coactingly mounted thereon, and Fig. 5 is an end elevation of the parts so shown in said Fig. 4.

Similar numerals of reference denote corresponding parts throughout the several views.

My invention comprises two coacting devices, separately shown in said Figs. 2 and 3, and also shown as associated coactingly with each other and with wringer rolls in said Figs. 4 and 5. The two devices are of somewhat similar forms and dimensions and each device has like inverted J-shaped longitudinally and horizontally spaced hangers, the hangers 1 of one device being reversed in position relative to the like hangers 7 of the other device. Each hanger 1, therefore, has its upper part curved semi-circularly to provide a shorter depending member 2, while in like manner, each hanger 7 has its upper part curved semi-circularly in an opposite direction to provide a shorter member 8. The lower ends of the longer members 7 are rigidly connected to the extremities of the longitudinal horizontal bar 9, preferably of rectangular or polygonal cross section. This bar forms the only connection between said hangers 7-8.

The lower ends of the other hangers 1 are rigidly connected to a like longitudinal horizontal bar 4. Another like longitudinal

horizontal bar 3 rigidly connects the middles of the upper semi-circular parts of said hangers 1. At locations near the beginnings of the curves of bending of said hangers 1, 60 the hangers are punched out to provide horizontally projecting parts or shelves 6 partially cut away at openings 5.

The hangers 1 are first mounted upon the ends of the upper roll 11 of the wringer 65 10 by hanging their semi-circular parts 2 thereupon contactingly so that the hanger members 1 depend to locate the lower longitudinal bar 4 parallel with and in contact with one side of the lower roll 12. The other 70 device is mounted in a similar manner with its curved member 8 overhanging the upper roll 11 but not in direct contact therewith, as the extremity of the member 8 rests upon the shelf or projection 6 of the hanger 1 75 75 abutting thereagainst on its inner face. The longitudinal bar 9 of said hangers 7 is positioned parallel and in contact with the opposite side of said lower roller 12, directly opposite the other like bar 4. It will 80 be seen that the curved members 8 are supported off center on said projection 6 which causes the lower parts of the members 7, together with the bar 9, to move toward and keep said bar 9 in contact with said lower 85 roll 12 by the action of gravity. The weight of this device upon said projection 6 also tends to swing the other bars 4 into contact with the opposite side of the roll 12 so that said pair of devices coactingly and automatically retain their positions with their bars 9 and 4 in contact with said lower roll. Said longitudinal bars form abutments which deflect and prevent clothes becoming enwrapped about either roll. These 95 devices are operative with the manually actuated wringer shown in Fig. 1, but are especially useful when employed upon rolls rotated by an electrical or other prime 100 motor.

Having described my invention, what I claim as new and desire to secure by Letters Patent, is:

1. A device of the character described, comprising separable coacting hangers 105 adapted to be removably supported upon the upper roll of a pair of wringer-rolls, and having deflector-members respectively extended along the top of the upper roll and along opposite sides of the lower roll. 110

2. A device of the character described, comprising separable coacting hangers

adapted to be positioned on opposite sides of a pair of upper and lower wringer-rolls, with one hanger suspended on the upper roll and the other hanger supported on the 5 first-mentioned hanger, the first-mentioned hanger having a deflector-member extended along the top of the upper roll contactingly, and each of said hangers having a deflector-member which extends contactingly along 10 the side of the lower roll which abuts upon the hanger.

3. A device of the character described, comprising a pair of inverted J-shaped hangers suspended upon the upper roll of 15 a pair of upper and lower wringer-rolls and rigidly connected by a bar which extends contactingly along the upper roll, said hangers having longitudinal projections on their longer arms, and a pair of J-shaped 20 hangers positioned reversely relative to the first-mentioned hangers about said upper

roll with the extremities of their short arms supported movably upon said projections, each pair of hangers having a bar rigidly connected between them and extended contactingly along the abutting side of the 25 lower roll.

4. A device of the character described, comprising a pair of deflector-devices positioned about a pair of wringer-rolls, one device being movably supported on one roll, and the other device being movably supported on the first-mentioned device and 30 separably movably engaged therewith whereby the lower parts of the devices are impelled by their gravity coactions to approach the roll therebetween, said devices having deflector members positioned along said roll. 35

Signed at Waterloo, Iowa, this 14th day of July, 1919.

LOUIS F. DOELLINGER.
